UNITED STATES PATENT OFFICE.

JAMES McCUTCHEON COLEMAN, OF WESTMOUNT, QUEBEC, CANADA.

DUMP-CAR CONSTRUCTION.

1,027,241.

Specification of Letters Patent.

Patented May 21, 1912.

Application filed July 3, 1911. Serial No. 636,703.

To all whom it may concern:

Be it known that I, JAMES McCUTCHEON COLEMAN, resident of 356 Olivier avenue, in the city of Westmount, in the Province of Quebec, in the Dominion of Canada, a citizen of the United States of America, have invented certain new and useful Improvements in Dump-Car Construction; and I do hereby declare that the following is a full, clear, and exact description of the same.

The invention relates to improvements in dump car construction, as described in the present specification and illustrated in the accompanying drawings that form part of the same.

The invention consists essentially in the novel construction and arrangement of parts, whereby a swinging hopper door is made to fit tightly into a dump opening and to hang freely in its open position.

The objects of the invention are to devise a swing door, which may be readily closed into a dump opening and form a tight joint to prevent the loss of grain or granulated cargo, and generally to provide a cheap, convenient and durable form of door mechanism for dump cars.

In the drawings, Figure 1 is a sectional side view of a chute, showing the dump opening and a door in its closed position. Fig. 2 is an enlarged sectional detail of the joints, showing the door in its open position. Fig. 3 is an enlarged sectional detail of the cross beam, joining the set of doors and the end of the operating arm connected thereto. Fig. 4 is a front elevation of the hoppers, showing the arm extending therebetween to the cross beam connecting the two doors. Fig. 5 is a perspective detail of the door. Fig. 6 is a perspective view of the loop and ring. Fig. 7 is an enlarged elevational detail of the lower end of a chute showing one of the locking dogs engaging a door. Fig. 8 is an enlarged sectional view on the line A—B in Fig. 4. Fig. 9 is a side elevational detail of the upper end of a chute showing part of the operating mechanism and a locking arrangement.

Like numerals of reference indicate corresponding parts in each figure.

Referring to the drawings, 1 are the side walls of the chute, 2 the bottoms thereof, 3 the end walls, said end walls terminating at the dump openings 4, said chutes being in substantially parallel arrangement and hav-

ing the dump openings in alinement. 5 is an outturned flange from the lower end of the upper portion of an end wall 3, in each of said chutes. 6 is a parallelly arranged outturned flange adjacent to the outturned flange 5 and forming therewith a pocket. 7 is a flange parallel with the bottom 2 and forming therewith a pocket. 8 and 9 are side flanges, forming with said side walls 1, 65 pockets connecting the pockets at the upper and lower ends of said dump opening.

10 and 11 are flanges extending inwardly from the inner face of the door 12 completely therearound and forming a pocket 70 into which the flange 6, the bottom 2 and the sides 1 are introduced in the closed position of the door.

13 is a bracket rigidly secured to an upper end wall 3.

14 is a bracket rigidly secured to the door 12 intermediate of the height thereof.

15 is a loop secured in the bracket 13 and the bracket 14 at the upper end of the door and in its closed position closely fitting over 80 said top end of the door and in its open position, allowing each door to swing free.

16 is a cross beam, rigidly secured to the outer face of each door 12.

17 is an arm pivotally secured at one of 85 its ends to the beam 16 between the chutes and at the other end secured to the gear 18, said gear coacting with the worm 19, the latter being mounted on the shaft 20. The gear 18 is journaled in the bearings 21 and 90 the shaft 20 in the bearings 22 supported from the under side of the car body.

23 is a crank for operating the shaft 20.

24 are dogs, each dog, being pivotally secured to the side wall of the chute having 95 a squared slot 25 locking to a squared shaft 26 extending from the lower ends of each door 12.

27 is a dog having a squared slot 28 and pivotally supported from the car body and 100 adapted to engage the square portion of the shaft 20 and lock said shaft.

In the operation of this car, the crank 23 is turned, which throws the arm 17 rearwardly when the doors are in their closed 105 position, and this forces both doors to their open position, that is, it takes the flanges out of the pockets and breaks the joints and as the door opens farther, the loop hinge connections permit the doors to drop and 110 swing to an open position and when the doors are brought back again, the hinges

will draw up the doors so that the flanges will be brought into the proper position to enter the several pockets and thus a grain tight joint is secured.

5. What I claim as my invention is:
1. In dump car construction, a car body having a dump opening and double plate formation around said dump opening forming pockets and a door having a link hinge
  - 10 support from one end and double plate inwardly extending flanges forming pockets, said hinge being adapted to draw said flanges and pockets into register in the closing operation.
  - 15 2. In dump car construction, a car body having a dump opening and double plate formation around said dump opening forming a continuous pocket and a swinging door having a loop hinge supporting it from one
  - 20 of the sides of the dump opening and double plate flange formation extending from an inside face and forming a continuous pocket, said door being adapted to swing freely from said opening and in closing, to draw
  - 25 into place, by means of said hinge connection, said flanges from the door entering the dump opening pocket, and said flanges from around the edge of the dump opening entering the door pocket.
  - 30 3. In dump car construction, a car body having a chute therebeneath and a dump opening in the end wall of said chute, said end wall and bottom and sides of the chute having double plate formations formed by

outwardly extending flanges around said dump opening, a door, having around the outer edge thereof, parallel double flanges extending from the inside face forming a pocket, a hinge formed by a loop and brackets fastened to the upper portion of the end wall of the chute and to the door respectively, and means for operating said door.

4. In dump car construction, a car body having a pair of substantially parallel chutes therebelow and dump openings in the end walls of said chutes, said chutes having a double plate formation formed by flanges around said dump opening, a pair of doors having double plate formations formed by flanges extending inwardly from the inside face and coacting with the aforesaid double plate formation, hinges securing said doors to the upper portion of the end walls of the chutes and formed with brackets and loops connecting the brackets, a cross beam rigidly secured to and connecting said doors, an arm pivotally secured to said beam at one end, and a worm and gear mechanism connected to the other end of said arm suitably operated.

Signed at the city and district of Montreal, Quebec, Canada, this twelfth day of June, 1911.

JAMES McCUTCHEON COLEMAN.
